UNITED STATES PATENT OFFICE.

GEORGE W. SWIFT, JR., OF BORDENTOWN, NEW JERSEY, ASSIGNOR TO GEORGE W. SWIFT, JR., INC., OF BORDENTOWN, NEW JERSEY, A CORPORATION OF NEW JERSEY.

WEB-PUNCHING MECHANISM.

Application filed February 19, 1923. Serial No. 620,116.

To all whom it may concern:

Be it known that I, GEORGE W. SWIFT, Jr., a citizen of the United States, and resident or Bordentown, county of Burlington, and 5 State of New Jersey, have invented certain new and useful Improvements in Web-Punching Mechanisms, of which the following is a specification.

The present invention relates to an improved mechanism for punching or otherwise marking a succession of printed forms upon a traveling web. The improved mechanism may be used for producing any desired successive impressions upon a web or 15 series of sheets, but is particularly applicable for punching holes at the desired intervals in a traveling web.

The improved punching or marking mechanism comprises a pair of oscillatory shafts 20 mounted in parallel relation and having means acting through one shaft for imparting a to and fro oscillating motion and means acting through the other shaft for causing intermittent bodily movement of one 25 shaft toward and away from the other. The relatively movable oscillatory shafts carry either one or both printing, punching or other marking devices for acting upon a web or sheets that pass between the shafts. 30 The devices for oscillating the shaft and for bodily moving one shaft toward and away from the other are preferably actuated from the common drive, which is operated at a proportional speed with relation to the feed 35 of the web or sheets. This proportional speed will differ for different form lengths which are operated upon and for the ready adjustment of the speed of operation of the punching or numbering shafts with relation 40 to the feed of the web. I provide a changeable proportional gear mechanism of any suitable form. The shaft oscillating devices are adjustable independently of their driving mechanism to accurately adjust the 45 speed of oscillation to the surface speed of the web or sheets, without regard to the adjusted periodic bodily movement of the shaft.

More specifically the preferred embodiment 50 of the improved machine includes an oscillatory shaft mounted in fixed bearings, a companion shaft mounted in adjustable

eccentric bearing bushings, segment gears connecting the two shafts, an adjustable crank drive acting through the shaft in fixed 55 bearings, gearing for rotating the eccentric bushings for causing periodic bodily movement of one shaft toward and away from the other, and a common drive mechanism actuating the crank drive and eccentric 60 bushing. A changeable proportional gearing is arranged between the common drive and the main drive shaft of the machine from which the web or sheets are driven.

In order that the invention may be fully 65 understood it will first be described with reference to the accompanying drawings and afterwards pointed out more particularly in the annexed claims.

In said drawings:

Fig. 1 is a detail plan view of a section of 70 a web machine to which the improved mechanism in the form of a multiple web punch is applied, this view being taken in the direction of the arrow 1 of Fig. 2.

Fig. 2 is a detail side elevation of the 75 same mechanism.

Figs. 3 and 4 are detail sectional views taken on the lines 3—3 and 4—4 of Fig. 2.

Figs. 5, 6 and 7 are detail sectional views 80 taken respectively on the lines 5—5, 6—6 and 7—7 of Fig. 1.

Figs. 8, 9, 10 and 11 are diagrammatic views illustrating the operation of the improved punching mechanism.

The improved mechanism is shown as 85 part of a machine arranged to print, punch and number forms or bills upon a traveling web or succession of sheets of paper. The embodiment of the present invention is a 90 web punching mechanism arranged to punch the desired holes in the proper location in the printed forms of a traveling web.

1 and 2 are the side frames of the machine. 10 is a transverse shaft journalled 95 in fixed bearings in the side frames 1, 2 and carrying between its ends a number of adjustably mounted punch members 11. 15 is a shaft journalled at its opposite ends in eccentric bushings 16 parallel with the shaft 100 10 and carrying a number of adjustably mounted die members 17, which cooperate with the punch members 11 referred to.

The eccentric bushings 16 are journalled

in suitable bearings in the side frames 1 and 2 so that in their rotation they will cause the shaft 15 to move bodily toward and away from the shaft 10.

5 20 indicates a web or series of sheets of paper passing between guide rolls 21 and up between the shafts 10 and 15 in the plane in which the punch and die members operate for punching openings in the passing 10 web.

Shaft 10 has adjustably secured to its projecting end a crank arm 25 mounted upon a split collar 26 by which it is attached to shaft 10. A pitman 28 connects crank pin 25 with 15 a crank pin 30 formed upon a disk 31 adjustably mounted in an eccentric recess 32 by means of set screws 33. A disk 35 is mounted upon the projecting end of a shaft 40 freely journalled in the side frame 1 and 20 carrying at its opposite end a beveled gear 41 meshing with and driven by a similar gear 42, which is adjustably secured to a driving shaft 50 by means of a splined hub 43 and set screws 44. By loosening the screws 25 44 the gear 42 can be adjusted around shaft 50 and afterwards securely fastened in the desired adjusted position.

60 and 61 are intermeshing gear segments keyed respectively upon the shafts 10 and 15 30 for oscillating the latter from the former.

Each of the eccentric bushings 16 for shaft 15 is formed with a flanged outer end 16^a upon which is adjustably mounted a ring gear 65 secured in the desired position upon 35 the flanged end of the bushing by means of a series of flanged set screws 66 seated in gears 65 and engaging end 16^a. This ring gear 65 is in constant mesh with a similar ring gear 70 adjustably mounted upon a flanged 40 bearing bushing 75 by means of flanged set screws 71. The bushing 75 is freely journalled in one of the side frames and is splined or keyed as indicated at 76 to the end of a transverse shaft 80 carrying at one end a beveled gear 85 meshing with a similar gear 86 adjustably mounted upon shaft 50 by 45 means of a splined collar 87 and set screws 88.

The specific description of geared bushings 16 and 76 is with reference to one end only of the shafts 15 and 80, but it should be understood that the same arrangement of geared bushings is also provided at the opposite end of these shafts so that the rotation of bushings 16 at opposite ends of shaft 15 will cause an even bodily movement of shaft 15 toward and away from shaft 10.

The common drive shaft 50 is suitably journalled in horizontal position upon the 60 side frame 2 by means of bearing brackets 90. This shaft 50 must be driven by suitable gearing from the main drive shaft of the machine. The speed of shaft 50 must have a proper proportional relation to 65 the surface speed of the web to be operated

upon. This proportional speed will differ with different length forms that have been printed upon the web, since the periodic bodily movement of shaft 15 toward shaft 10 determines the number of punching operations upon the web. In Fig. 1 is shown more or less diagrammatically a gear 95 upon shaft 50 driven through intermediate gear 96 upon a stud shaft that is adjustable circumferentially of gear 95 and a gear 97 70 upon the main driving shaft 100. The gear 95 is made removable and changeable so that by mounting the proper size of gear 97 upon shaft 100 the desired speed ratio between the punching operation and traveling 75 web can be obtained.

In the operation of punching a web, it will be understood that the rotation of eccentric bushing 16 moves shaft 15 carrying the die members toward and away from shaft 10 carrying the punch members. As the punch and die members come into cooperative relation the shafts 10 and 11 are rocked by the crank and pitman device described, to cause the punch and die members to travel 80 in the same direction and at the same speed as the web 20 which is fastened between them. At the completion of each punching operation the bushings 16 separate the shaft 85 sufficiently to disengage the punch and die members for their return stroke.

It will be understood that the adjustments shown enable the operator to first determine the necessary periodic operation of the punches to suit the length of forms to be 100 operated upon. This is accomplished by mounting the proper size of driving gear 97 upon the shaft 100. It then becomes necessary to adjust the cranks 25 and 30 to get the proper throw and speed of the crank 105 when the punch and die members are brought into cooperative relation. These parts can be adjusted to nicely to cause the punch and die members to operate at the exact speed of the traveling web upon which 110 they operate. Figs. 9 and 11 show plan views of two webs with different form lengths indicated upon them, the forms of Fig. 9 being twice the length of those in Fig. 11. It will be understood that to punch 115 the short form length of Fig. 11, it is necessary that the mechanism be adjusted to operate twice as fast as for those form lengths shown in Fig. 9, that is the number of bodily movements of shaft 15 toward shaft 10 in 120 punching Fig. 11 form lengths must be double that required in punching Fig. 9 form lengths. This is true on the assumption that the speed of the web operated upon is the same in both cases. Figs. 8 and 10 show 125 respectively the adjustment for these two form lengths illustrated in Figs. 9 and 11. It will be noted in Fig. 8 that the throw of the crank for oscillating the shafts 10 and 15 130 is greater and faster when operating upon

the form lengths of Fig. 9 than it is when operating upon the form lengths of Fig. 11, due to the change in speed of the drive shaft 50. The actual speed of oscillation of shafts 10 and 15 is, however, the same in both cases.

I claim :

1. In a machine of the character set forth, the combination of a pair of oscillatory shafts, means for axially oscillating said shafts, and means for intermittently moving one shaft toward and away from the other. 10
2. In a machine of the character set forth, the combination of a pair of oscillatory shafts carrying cooperating punch and die devices, means for simultaneously oscillating said shafts, and means for intermittently moving one shaft bodily toward and away from the other. 15
3. In a machine of the character set forth, the combination of two shafts mounted to oscillate to and fro adjacent to the path of a web or sheets, and means for moving one of said shafts toward and away from the web or sheet path during the said to and fro operation. 20
4. In a machine of the character set forth, the combination of two shafts mounted to oscillate to and fro adjacent to the path of a web or sheets, means for moving one of said shafts toward and away from the web or sheet path during the said to and fro operation, and cooperating punch and die devices mounted respectively upon said shafts. 25
5. In a machine of the character set forth, the combination of two shafts mounted to oscillate to and fro adjacent to the path of a web or sheets, adjustable means for moving one of said shafts toward and away from the web or sheet path, and cooperating punch and die devices mounted respectively upon said shafts. 30
6. In a machine of the character set forth, the combination of an oscillatory shaft mounted in fixed bearings, a cooperating oscillatory shaft mounted in rotary eccentric bearings, intermeshing segment gears mounted upon said oscillatory shafts, means for rotating said eccentric bearings, and means for oscillating said shafts. 35
7. In a machine of the character set forth, the combination of an oscillatory shaft mounted in fixed bearings, a cooperating oscillatory shaft mounted in rotary eccentric bearings, intermeshing segment gears mounted upon said oscillatory shafts, adjustable means for rotating said eccentric bearings, and adjustable means for oscillating said shafts. 40
8. In a machine of the character set forth, the combination of an oscillatory shaft mounted in fixed bearings, a cooperating oscillatory shaft mounted in rotary eccentric bearings, 45

tric bearings, intermeshing segment gears 65 mounted upon said oscillatory shafts, means for rotating said eccentric bearings, adjustable means for oscillating said shafts, suitable change gear driving mechanism, and cooperating punch and die devices carried by said shafts. 70

9. In a machine of the character set forth, the combination of an oscillatory shaft mounted in fixed bearings, a second oscillatory shaft mounted in eccentric bearings, 75 a crank mechanism connected with the first named of said oscillatory shafts, gears for rotating said eccentric bearings, and a drive shaft geared to said crank and said eccentric operating gears. 80

10. In a machine of the character set forth, the combination of an oscillatory shaft mounted in fixed bearings, a second oscillatory shaft mounted in eccentric bearings, intermeshing segment gears mounted 85 upon said oscillatory shafts, a crank mechanism connected with one of said oscillatory shafts, gears for rotating said eccentric bearings, and a drive shaft geared to said crank and said eccentric operating gears. 90

11. In a machine of the character set forth, the combination of an oscillatory shaft mounted in fixed bearings, a second oscillatory shaft mounted in eccentric bearings, a crank mechanism connected with one of said oscillatory shafts, gears for rotating said eccentric bearings, a drive shaft geared to said crank and said eccentric operating gears, means for adjusting the speed of said drive shaft, and cooperating punch and die devices mounted upon said oscillatory shafts. 100

12. In a machine of the character set forth, the combination of an oscillatory shaft mounted in fixed bearings, a second oscillatory shaft mounted in rotary eccentric bearings, a crank arm adjustably mounted upon one of said oscillatory shafts, a crank member carrying an adjustable crank pin, a pitman connecting said adjustable crank pin with said adjustable crank arm, and a drive shaft geared to said crank member and said eccentric bearings. 105

13. In a machine of the character set forth, the combination of an oscillatory shaft mounted in fixed bearings, a second oscillatory shaft mounted in rotary eccentric bearings, a crank arm adjustably mounted upon one of said oscillatory shafts, a crank member carrying an adjustable crank pin, a pitman connecting said adjustable crank pin with said adjustable crank arm, a drive shaft geared to said crank member and said eccentric bearings, means for adjusting the speed of said drive shaft, and cooperating punch and die devices mounted upon said oscillatory shafts. 115

14. In a machine of the character set forth, the combination of an oscillatory

shaft mounted in fixed bearings, a second oscillatory shaft mounted in rotary eccentric bearings, a crank arm adjustably mounted upon one of said oscillatory shafts, a crank disk carrying an adjustable crank, a pitman connecting said adjustable crank with said adjustable crank arm,

a drive shaft geared to said crank disk and said eccentric bearings, means for feeding a web or sheets between said oscillatory shafts, and cooperating punch and die devices mounted upon said oscillatory shafts.

GEORGE W. SWIFT, JR.
